ROTARY WELL DRILLING MACHINERY

Charles L. Allen, Portland, Oreg., assignor to thirty-five per cent to Victor Thomas Wiglesworth, Portland, eight per cent to H. Victor Adix, Gresham, seven and one-half per cent to Garfield Voget, Hubbard, and four per cent to Fred H. Thompson, Salem, and two per cent to Ellis F. Lawrence, Portland, Oreg.

Application April 17, 1940, Serial No. 330,012

1 Claim. (Cl. 255—4.8)

My invention relates to improvements in rotary well drilling machinery.

The invention is comprised primarily of a casing made up of a plurality of sections and removably secured together.

An electric motor is disposed within the top one of the casings, with means being provided for conducting electric energy through a supporting cable, through the guide spindle to the motor and pumping and screening instrumentalities and speed reducers being disposed within the casing to impart and drive rotation to cutter heads that are disposed upon the oppositely disposed ends of the casing.

I provide spuds upon the exterior of the casing, with pumping and expanding means being provided for outwardly extending the spuds to form contact with the sides of the well hole being drilled to prevent the rotation of the casing within the well being drilled.

The primary purpose and object of my invention is to provide oil well drilling instrumentalities that are rugged in construction, that are self-contained, that are adapted for drilling on the top and bottom end of the casing, with equal facility, one that will permit the circulation of drilling mud through the casing, with screening facilities being provided within or without the casing, and one that will have a long and useful life, with practical freedom from operating mechanical annoyances.

A still further object of my invention is to provide expandable spuds on the outside of the casing that will maintain the casing of the drilling instrumentation free of rotation during the normal drilling operation.

A still further object of my invention is to provide a drilling head at each end of the casing that will drill a well of larger diameter than that of the casing itself.

A still further object of my invention consists in placing within the casing pumping means that will be automatic in operation, having for its purpose the maintaining of spuds disposed upon the outside of the casing in expanded position to prevent the rotation of the casing during drilling.

With these and incidental objects in view, the invention consists in certain novel features of construction and combination of parts, the essential elements of which are set forth in the appended claim, and a preferred form of embodiment of which is hereinafter shown with reference to the drawing which accompanies and forms a part of this specification.

In the drawing:

Fig. I is a fragmentary sectional side view of the top end of the device.

Fig. II is a fragmentary sectional side view of the lower end of the device.

Fig. III is a sectional end view of the device. This view is made adjacent the inside of the head of the top end of the device, the view being taken on line 3—3 of Fig. I, looking in the direction indicated.

Fig. IV is a sectional end view of the device. This view is made to illustrate the drive for the shaft for rotating the drilling head disposed at the lower end of the device. It also illustrates the spuds disposed at the outside of the shell that are provided for preventing the rotation of the assembly within the hole being drilled. This view is taken on line 4—4 of Fig. I, looking in the direction indicated.

Fig. V is a sectional end view of one of the spuds disposed upon the outside of the shell. In this view is illustrated an expandable chamber having an expandable bag disposed therein that is used for outwardly extending the spud when desired, the purpose and object being to prevent the rotation of the shell within the hole being drilled.

Like reference characters refer to like parts throughout the several views.

In Figs. I and II, I have shown a casing made up of a top section 1 and a lower section 2, with the respective sections being secured together by any suitable coupling connector 3. Suitable fastenings 4 are provided for securing the lower end of the coupling to the bottom end of the casing, and suitable counter sunk bolts 5 are used for securing the top end of the casing 1 with the coupling 3.

While I have here shown the casing as being comprised of but two pieces, I do not wish to be limited in the application or in the construction of my device to but two joints of casing, as a greater number may also be employed.

I place one or more electric motors, here shown as two in number at 6 and 7 within the casing. The motors are spaced apart and have a common longitudinal center line, with the armature shafts of the same being secured together by flanged couplings 8 and 9.

A top head 10 is removably secured to the top end of the casing, and the same may be threaded thereinto or be secured thereto by suitable bolts 11. A suspending and pulling stem 12 passes through the head 10 and is journaled relative

thereto by suitable anti-friction bearings 13. A

drilling head 14 is disposed at the top end of the casing.

A tubular sleeve 15 is disposed about the stem 12, and the drilling head 14 is secured to the top end of the sleeve 15. A suitable stuffing gland 16 is disposed about the stem 12 and superposed the sleeve, and the stuffing gland is threadably and adjustably secured to the top end of the drilling head 14. The stem 12 is secured on its lower end to a spider 12A. The spider 12A is secured to a head 12B by any suitable fastening means, as through the use of bolts or rivets 12C.

A cap 17 is threadably and adjustably secured to the top end of the stem 12, and the suspending cable 18 has an enlarged head 19 disposed upon its lower end, which is suitably journalled and housed within the top of the cap 17.

The electric conducting power line 20 passes longitudinally of the stem 12 and conducts power from the cable 18 into the electric motors 6 and 7 disposed within the casing. The lower end of the tubular sleeve 15 is flanged, as illustrated at 21, and a suspending driving head 22 is secured to the flange 21 of the sleeve 15, the same being removably secured thereto by suitable connecting bolts 23.

The top end of the anti-friction bearing 24 is threaded into the lower face 25 of the head 10, and the top surface of the driving head 22 is finished, and against which the lower end of the anti-friction bearing 13 rests to form a suitable bearing connection between the respective heads 10 and 22.

A driving pinion 26 is disposed upon the upper end of the armature shaft 27, and the driving pinion 26 coacts with and drives a plurality of idler gears, here shown as three in number at 28, 29, and 30. Each of the gears 28, 29, and 30 rotate about a single shaft, as illustrated at 31, 32, and 33. A driving pinion is secured to each of the gears 28, 29, and 30, as illustrated at 34, 35, and 36, and an internal gear husk 37 is mounted upon the lower end of the head 22 and is secured thereto, and as the pinions 34, 35, and 36 are rotated, the gear husk 37 is rotated and simultaneously therewith the sleeve 15 and the drilling head 14 secured thereto.

The respective diameters of the gears and pinions determines the relative speed ratios of the drilling head 14 to that the driving motors 6 and 7, and this desired ratio of speed is determined by the character of material to be drilled and other drilling conditions.

The respective stuffing boxes 16 and 38 prevent the admission of material into the shell 1 at its upper end.

I place a supporting diaphragm 39 within the lower end of the shell 1 and secure the same to the shell 1 by any suitable counter sunk bolts 40. The armature shaft 41 passes through the diaphragm 39, and a driving pinion 42 is mounted upon the lower end of the armature shaft. The driving pinion 42 coacts with and drives a plurality of planetary gears, here shown as three in number at 43, 44, and 45.

The gears 43, 44, and 45 coact with a ring gear 46. The ring gear 46 is fixedly secured to the inside of the lower end of the casing 1, and a driving disk 47 is disposed immediately below the planetary gears, and shafts 48A, 49A, and 50A are secured to the plate 47, upwardly extend therefrom and act as journal shafts for the gears 43, 44, and 45; as the gears 43, 44, and 45 coact with and travel about the ring gear 46, the driving disk 47 is also rotated.

The driving disk 47 is fixedly secured to the shaft 48 and the shaft 48 passes through the coupling connector 3. A stuffing box 49 of the conventional type is disposed about the shaft 48. The stuffing box operates in conjunction with a tube 50 disposed centrally of and upon the under side of the coupling connector 3.

The shaft 48 is tubular upon its lower end, as illustrated at 51, and a screen 52 is disposed about the tubular portion of the shaft 48. The screen is secured to a ported sleeve 53, with a plurality of ports 54 being disposed within the sleeve, with a like number of ports being disposed within the shell 55 of the tubular portion of the shaft 48, so that pumped fluid may flow through the screen and through the respective ports into the tubular portion 51 of the shaft 48.

The coupling connector 3 separates the top portion of the casing 1 from the bottom portion 2 of the casing, and a plurality of ports 56 are disposed within the top end of the casing to and immediately below the coupling connector 3, so that fluid, as mud, disposed within the bottom of the hole will flow freely into the bottom end of the casing and coarse drilled material will be trapped within the casing, with the screened fluid passing through the screen into the tubular portion 51 of the shaft 48 and thence into the centrifugal pump 57.

The pump 57 may be a centrifugal pump or it may be a rotary pressure pump and it is housed within a suitable pump housing 58 disposed upon the lower end of the casing 2. The pump 57 has a ported head 59 disposed therein, and the pump 57 is secured to the lower end and to the tubular end of the shaft 48.

The pump housing 58 and the casing 2 is closed upon its lower end by a head 60, and a husk 61 is removably secured, as by being threadedly attached thereto, as illustrated at 62.

A plurality of roller bits 63 are placed within the husk 61, and each of the roller bits are suitably journalled within the husk by bearings 64 and fluid pumped by the pump passes and is discharged through the lower end of the tubular shaft and enters and is discharged through a port 65 which is disposed within the husk so as to permit the pumped fluid being circulated and discharged immediately within the area of the roller bits and at the bottom of the well being drilled.

It will be noted that a relatively large sump 66 is disposed within the pump housing into which the fluid being pumped flows from the ports 67 disposed in the outer periphery of the pump 57.

It will be noted that the head 60 acts as a head not only for the pump housing but for the lower end of the casing 2 as well. The head is secured to the pump housing 58 by suitable fastening bolts 68, and the head is also secured to the lower end of the casing 2 by suitable fastening bolts 70.

I provide a plurality of channels 71, 72, and 73, here shown as three in number and place the same at one or more points vertically along the outer casing 1 and 2 and secure the same to the casing by any suitable fastening means.

The channels 71, 72, and 73 are each comprised of side walls 74, with a relatively broad surface 76 forming the back, with the back being directly engageable upon the outer surface of the respective casings. The outer surface of the broad side of the channel is curved similarly to that of the casing to facilitate the same en-

gaging upon the outer surface of the casing members.

The side walls 74 are made in the form of jaws, with projecting surfaces 77 and 78 being provided, and spuds are provided. The spuds may be made in the form of bars 79, 80, and 81, as illustrated in Fig. IV, each having a relatively broad base, as illustrated at 82, 83, and 84, with the outer edges of the spuds engaging the inner surface of the spud holders, with projections 85 and 86 being provided, as illustrated in Fig. V and having knife edges 87 running longitudinally of the outer surface of the spud.

An expansible bag 88 is placed within either of the spud holders and immediately behind the spuds, with the expansible bag being hollow to receive an expanding fluid therein. The expanding fluid is delivered into the expansible bag by a suitable tube 89.

A suitable fluid holder 90, as illustrated in Fig. I, is suitably positioned within the casing, and a fluid pump 91 is also disposed within the casing, with communication being effected between the fluid holder 90 and the pump 91 by a pipe or tube 92, with the tube 89 being in communication with and receiving its fluid from the pump 91.

The pump 91 is of any suitable make, as a rotary or gear pump, and the shaft 92A of the pump is supported and suitably journaled within the supporting diaphragm 39.

A driven gear 93 is disposed upon the shaft 92A and a pinion 94 is mounted upon the armature shaft 41, with the pinion 94 driving the gear

93, to thereby drive the pump 91 for the delivering of fluid under pressure from the pump 91 through the tube 89 into the expansible bag 88. Instead of providing the spuds with knife edges, as illustrated at 87, I may provide a plurality of rollers 95 in spaced relation along the spud, with the rollers coming to knife edges, as illustrated at 96, and with the same being mounted upon suitable supporting shafts 97, as illustrated in Fig. V.

10 A pressure regulating valve 98 is disposed within the tube 89, to thereby prevent the developing of unnecessary pressure within the expansible bag 88, with a tube 99 being disposed between the pressure regulating valve and the fluid holding tank 90 to by-pass the pumped fluid directly into the fluid holding tank 90.

20 While the form of mechanism herein shown and described is admirably adapted to fulfill the objects primarily stated, it is to be understood that it is not intended to confine the invention to the embodiment herein shown and described, as it is susceptible of embodiment in various forms, all coming within the scope of the claim which follows.

25 What I claim is:

20 In a device of the class described, comprising in combination, a well drill including a shell, spuds disposed on the outside of the shell and extending longitudinally of the shell, and hydraulic means disposed within the shell for forcing the spuds 30 outwardly from the shell.

CHARLES L. ALLEN.
